FOREIGN PATENT DOCUMENTS

FR 2 504 367 A1 10/1982

Primary Examiner — Derrick Holland*Assistant Examiner* — Lauren Calve(74) *Attorney, Agent, or Firm* — Kilpatrick Townsend & Stockton LLP(57) **CLAIM**

The ornamental design for a device for applying a formulation to skin, as shown and described.

DESCRIPTION

FIG. 1 is an exploded perspective view of a device for applying a formulation to skin shown in an open configuration, with a view of a cartridge for use in the device removed from the device; and,

FIG. 2 is a second perspective view thereof shown in a partially open configuration, with a cartridge inserted into the device.

The broken lines shown represent unclaimed subject matter and form no part of the claimed design.
